EDMUND BROWN, OF BURLINGTON, VERMONT, ASSIGNOR TO HIMSELF
AND GEORGE D. WRIGHT, OF THE SAME PLACE.

Letters Patent No. 78,050, dated May 19, 1868.

IMPROVED VEGETABLE-MASHER.

The Schedule referred to in these Letters Patent and making part of the same.

TO ALL WHOM IT MAY CONCERN:

Be it known that I, EDMUND BROWN, of Burlington, in the county of Chittenden, and State of Vermont have invented a new and improved Vegetable-Masher; and I do hereby declare that the following is a full, clear, and exact description thereof, which will enable others skilled in the art to make and use the same, reference being had to the accompanying drawings forming part of this specification, in which—

Figure 1 represents a front elevation of my improved vegetable-masher.

Figure 2 is a vertical transverse section of the same, taken on the plane of the line $x\ x$, fig. 1.

Figure 3 is a detail horizontal section of the same, taken on the plane of section $y\ y$, fig. 2.

Similar letters of reference indicate corresponding parts.

This invention relates to a new device for mashing boiled potatoes or other vegetables, and consists in the arrangement of a perforated inclined frame, and of a smooth presser, sliding and swinging thereon, all being so arranged that the mashed body or pulp of the potato, or other article, will be forced through the meshes or perforations of the frame, while the peels will not pass through the same, but will fall into a dish or pan placed for their reception.

A, in the drawing, represents a frame, from which two inclined parallel posts, B B, project upward. The frame is so arranged that it can be fastened upon or to a table, or otherwise, in a fixed position. Between the upper part of the posts B is held an inclined frame, C, in which a series of strong horizontal bars, $a\ a$, are arranged, which are so near together that no vegetable mass can pass between them in large lumps.

In front of the frame C is arranged, between the posts B, another inclined frame, D, which reaches below the frame C, as shown, and in which a series of parallel upright wires, b , is held, that rest on the front edges of the bars a , as shown. By the bars a and wires b is thus produced a perforated or net-work, instead of which a simple wire sieve, or a perforated plate, may be used, although the device shown is preferable on account of its simplicity, and because it can be more easily cleaned. The frames C D are both removable from between the posts B, so that cleaning may be facilitated. If net-work or perforated plates are used, one of the frames C D becomes superfluous.

E represents a block or board, with a smooth inner surface, which may be made still more smooth by receiving a metallic covering, c , as shown. The block or presser E is provided with an upward-projecting handle, d , and with two hooks, $e\ e$, that project to the front, as is clearly shown in fig. 2. This presser E may be moved up and down in front of the perforated plate or fabric $a\ b$, being guided between the upright side-bars $f\ f$ of the frame D. On these bars f is also held a sliding follower, F, which can, by means of a hook, g , or otherwise, be connected with the presser E during the up-and-down motion of the same, clearing the perforated plate or fabric behind the presser, and, in connection with the frames C D, bearing both the wires b and the bars a . On the posts B are secured pins $h\ h$, which can be made to engage the hooks e , as shown by red lines in fig. 2, to allow the presser to be oscillated.

The operation is as follows: A boiled potato is cut half through, and one half of it is placed with the cut surface upon the side $a\ b$, while the presser is swung down, as shown by red lines in fig. 2. The presser is then turned up against the sieve, forcing the mealy contents of the potato through the meshes of the sieve, while the peel will remain upon the sieve. The presser is then moved down between the posts B, and carries the peel down, so that the particles of flesh adhering to it may be removed, the follower F clearing them off the surface of the sieve. The peel, when it has reached the lower end of the frame D, drops into a receptacle, H, placed in front of the frame, as shown.

The fleshy substance pressed through the sieve falls upon an inclined board, i, and thence into a receptacle, I, or directly into the latter. The presser is then drawn up and turned down again, and another half potato is inserted, and treated as before. Instead of potatoes, other vegetables or articles may be mashed in this apparatus.

To prevent particles of the article mashed from adhering to the pressing-surface of the presser, a plate,

J, may be employed, which has a notched front edge, the wires fitting into the notches, while the sharp edge projects slightly in front of the wires, so as to scrape and clean the presser as the same travels up and down. The posts B, instead of standing in an inclined position, may be horizontal or downward inclined, or even vertical, as may be desired.

The potatoes mashed in this apparatus will come out beautifully prepared for the table, their appearance being superior to that of potatoes mashed by hand or other apparatus.

Having thus described my invention, what I claim as new, and desire to secure by Letters Patent, is—

1. A vegetable-masher, consisting of a perforated stationary frame and of a smooth swinging and sliding presser, as set forth.
2. The perforated frame of a vegetable-masher, when composed of the stiff bars *a a*, and of the wire rods *b b*, arranged in front of and crossing the bars *a*, substantially as herein shown and described.
3. The sliding and turning presser E, provided with hooks *e*, in combination with the pins *h* on the posts B, and with the perforated fabric *a b*, or its equivalent, all operating as set forth.
4. The device set forth in the foregoing clause, in combination with the sliding follower F, operating as specified.
5. The notched fixed scraper J, in combination with the frame D and with the presser E, all operating substantially as herein shown and described.
6. The combination of the frame A B and frames C D with the smooth swinging and sliding presser E, with the hooks *e* and pins *h*, with the follower F and scraper J, all made and operating substantially as herein shown and described.

EDMUND BROWN.
